REFRIGERATION

Dan H. L. Jensen and Emil Harman, Philadelphia,
Pa., assignors, by meane assignments, to Philco
Radio and Television Corporation, Philadelphia,
Pa., a corporation of Delaware

Application October 23, 1943, Serial No. 507,432

6 Claims. (Cl. 62—89)

This invention relates to new and useful improvements in refrigeration, and more particularly pertains to ice cube forming units especially adaptable to refrigerator cabinets having freezing compartments of the top access or well type.

In refrigerator cabinets of the type mentioned, the provision of means for forming ice cubes has met with certain problems and has given rise to numerous objections, not merely from the standpoint of manufacture, but also from the standpoint of practical usage. Heretofore it has been customary to mount within the freezing well of such a refrigerator cabinet one or more shelves for the support of conventional ice trays. However, an arrangement of this kind is objectionable because of the difficulties experienced in placing or removing the ice trays due to the restricted area available for that purpose. Moreover, the provision of shelves in a well-type freezing compartment deprives such compartment of considerable space with the result that the number of trays which may be used for freezing a supply of cubes at one time must, of necessity, be restricted to an extent that it is quite often impossible to freeze sufficient ice cubes to satisfy ordinary demands.

It is, therefore, one of the principal objects of the present invention to provide an ice cube forming unit which may readily be inserted into or withdrawn from a well-type freezing compartment and which does not require the use of a shelf for its support in such a compartment, the unit being so constructed that the space taken up by said unit when in ice cube freezing position within the compartment is reduced to the minimum, thereby permitting the use of a number of such units sufficient to produce enough cubes to satisfy ordinary requirements without cramming the available space.

Another important object of the invention resides in the provision of ice cube forming units capable of convenient arrangement within a well-type freezing compartment so that any one unit may easily be removed from and replaced into the compartment without disturbing or interfering with other units positioned within said compartment.

Still another equally important object of the invention resides in the provision of ice cube forming units, each having a plurality of cube molding members carried by a single supporting means in such a manner that the ice cubes in one member may be removed without effect on the ice cubes in the remaining members of the same unit, thereby permitting a relatively small number of ice cubes to be obtained without disturbing the whole content of the unit.

The invention is particularly characterized by the provision of a plurality of ice cube molding members carried by a support common to all of

said members in such manner that the latter will automatically assume an upright side-by-side relationship when the support is held in a generally horizontal position so that filling of the members with water for freezing into ice cubes may readily be accomplished and will automatically assume an upright superimposed relationship when the support is held in a generally vertical position for introduction and suspension of the water-filled members as a unit in a well-type freezing compartment.

The invention is further characterized by the provision of a series of ice cube molding members separately suspended on a support common to all of said members so that each member may be handled individually for removal of the frozen ice cubes therefrom or for refilling with water to be frozen into ice cubes.

Other objects and characteristic features of the invention as well as the details of construction and arrangement thereof will be apparent to those skilled in the art, from the following description based upon the accompanying drawings, in which:

25 Figure 1 is a perspective view illustrating the improved ice cube unit in use with a work height refrigerator cabinet having a well-type freezing compartment;

30 Figure 2 is a vertical cross-sectional view on a greatly reduced scale, taken through the refrigerator cabinet;

35 Figure 3 is a perspective view of an ice cube tray unit constructed in accordance with this invention, and showing the same in one of its positions;

40 Figure 4 is a view similar to Figure 3, but showing the unit in another one of its positions; and

45 Figure 5 is a perspective view of one of the ice molding members of the ice cube tray unit.

Referring now to the drawings, and more particularly to Figures 1 and 2 thereof, reference numeral 10 designates a refrigerator cabinet of the work-height type comprising wall and base portions insulated in accordance with conventional practice, and including a relatively deep lower refrigerated section 12 and a relatively shallow upper refrigerated section 14. A flat surface 16 extends outwardly of the shallow upper section 14 and covers the top portion of the deep lower section 12 in front of said upper section 14 to provide a work-table for the convenience of the user.

50 The lower refrigerated section 12 of the cabinet opens at the front and is provided with a door or closure 15 hinged at its lower edge, as indicated at 15a, so that said door may be dropped or swung downwardly for access into said section 12. On the other hand, the upper refrigerated section 14 opens at the top, and is provided with a lid or closure 17 hinged at the back as indicated

at 18 so that said lid may be lifted up for access into two "reach-in" areas 19 and 20. As shown, these areas 19 and 20 are defined by a separating wall 21 which, if desired, may be extended into the lower refrigerator section 12, thus dividing the latter into two areas, one of which communicates with area 19 and the other of which communicates with area 20. One of the areas in the lower section 12 may constitute a moist-cold food storage compartment, which may be readily provided, for example, by isolating said one area and providing cooling means therefor operating at temperatures slightly above freezing. Shelves, such as shown at 22 in Figure 2, may be suitably arranged in the lower section 12 to support food-stuff therein in the usual manner.

The lowermost area 23 of the lower section 12 of the cabinet is preferably separated from the main area 24 thereof by means of a wall 25 having relatively slight insulating effect. Moreover, in practice, the area 23 and area 24 are subdivided by insulated walls 26 and 27 to form a back chamber 28 which is entirely insulated except for a portion at the rear of the cabinet left open for the introduction, servicing and maintenance of a motor-compressor unit 29 of the usual refrigerating system. The area 23 is front opening and closed by means of doors 30 hinged to the cabinet, as indicated at 31, for outward swinging movement from a center position.

Arranged adjacent and about the inner wall surfaces of the area 18 in the upper section 14 of the cabinet 10, are the cooling coils 32 of the refrigerating system, thus forming within the "reach-in" area 19 of a well-type or top access freezing compartment which constitutes the freezing space of the refrigerator and accordingly, ice cubes may be produced therein. In addition, a container (not shown) may be placed in said space for the storage of frozen foods or the like. The area 20 being next to, but separated from, the freezing space or area 18 provides a convenient space for storage of bottles or unusually large and bulky articles and the area of the lower section 12 in direct communication with said area 20, provides a convenient space for dry-cold storage. In this event, the area of the lower section 12 below the area 18 may form the moist-cold space of relatively low temperature, as hereinbefore set forth.

As hereinbefore mentioned, ice cubes are to be produced within the freezing area 18 having the refrigerating coil 32 arranged therein. For this purpose and in accordance with the present invention, there is provided a plurality of ice cube tray units 33 constructed for insertion into said area in the manner more clearly illustrated in Figure 1 of the drawings. As shown more particularly in Figure 3, each unit 33 essentially comprises a frame 34 of generally rectangular configuration including side portions 35 and end bars 36. Disposed at spaced points along the length of the side portions 35 and projecting inwardly of the frame, are sets or pairs of oppositely disposed pins 37 which are adapted for pivotal engagement with supporting means, preferably in the form of hangers 38 provided at opposite ends with ice cube molding trays 39. The pins 37 and tray hangers 38 interengage one another at points located above the center of gravity of the trays 39 and centered with respect to the sides of said tray members so that the latter and their contents always remain in a level position, regardless of the angle at which the frame 34

may be held. Thus the frame 34 may be placed in a horizontal position, as shown in Figure 4 of the drawings, for filling either the entire unit or a single tray member and, after filling, the frame 34 may be placed in a vertical position, as shown in Figure 3, for insertion into the freezing area 18 of the refrigerator cabinet 10.

Preferably, one of the end bars 36 which normally is the top bar of the frame 34, extends 10 beyond the sides 35 of the latter as indicated at 40 so that when the frame 34 is inserted into the freezing area 18, said portions 40 will rest upon a supporting ledge in the cabinet structure, as illustrated, for example, in Figures 1 and 2.

Each of the tray members 39 is of elongated 15 shape having a length slightly less than the distance between the opposite side portions 35 of the frame 34 so that the trays 39 span the distance between said sides 35 and yet are free for detachable engagement with the frame pins 37 and for pivotal movement in relation to the frame 34 as previously described. Moreover, the width of the trays 39 in relation to the spacing of the pins 37 along the frame side portions 35 20 must be such that the trays are permitted to pivot into side-by-side relationship when the frame is horizontally disposed as in Figure 4. Each tray member 39 is provided with partitions 41 disposed transversely therein and positioned 25 at relatively spaced points along the length thereof to define ice cube forming sections 42.

In using the ice cube tray unit 33, the frame 34 may readily be supported in horizontal position, that is, in the position shown in Figure 4 30 in which the ice cube tray members 39 automatically assume the upright side-by-side position shown so that said trays 39 may all be filled at one time, if desired. The frame 34 then may be disposed in a vertical position, that is, in the 35 position shown in Figure 3 in which the ice cube tray members 39 automatically assume the upright superimposed position shown, and trays 39 inserted as a unit into the freezing area or 40 compartment 18, the frame still being held in 45 vertical position.

Since the ice cube tray units 33 are introduced and supported in vertical position in the freezing compartment 18, it will be appreciated that said 50 units occupy but relatively small space therein, and that a sufficient quantity of ice cubes may be produced at one time to satisfy ordinary demands and still leave ample free space within 55 said compartment for the storage of frozen food or the like without necessitating an unduly large freezing area.

Furthermore, as the ice cube tray units 33 are supported in vertical position within compartment 18 by the extending portions 40 of the top 60 end from bar 36, the necessity for supporting shelves, or the like, for said units 33 within the confines of the freezing compartment 18 is eliminated, thereby not only conserving space within 65 said compartment but facilitating the introduction and removal of any one of a plurality of units 33 without disturbing other units.

When it is desired to obtain ice cubes, a unit 33 may readily be lifted from the compartment 18 without interference with other units, and the cubes easily removed from each tray member 39 70 of the unit. Should but a few cubes be required, the unit 33 may be raised partially out of the compartment and only one of tray members 39 of the unit need be detached from the frame 34 to be emptied of its contents, whereupon the 75 detached and emptied tray member 39 may be

replenished with water and replaced on the partially withdrawn frame for reintroduction into the freezing compartment 19. In this connection, it is pointed out that the frames 34 may be so mounted as to be retained on the cabinet 10 but slideable thereon for movement in and out of the freezing compartment 19 so that each tray member 39 carried thereby may be removed and replaced individually on its frame.

While ice cube tray units 33 have been shown and described herein in combination with a refrigerator cabinet provided with a well-type freezing compartment, it is to be understood that the units 33 may be used in cabinets having other types of freezing compartment. Moreover, it is to be understood that the particular construction and arrangement of parts herein shown and described may be modified within the scope of the claims without departing from the invention.

We claim:

1. For a well-type freezing compartment, an ice forming unit adapted for introduction into and removal from said compartment, said unit comprising a substantially rectangular frame, means carried by the frame and disposed for engagement with portions of the compartment to suspend the frame substantially vertically therein, and a plurality of elongated tray-like members pivotally carried by the frame so that said tray members automatically assume an upright superimposed relationship upon placing the frame in substantially vertical position and automatically assume an upright side-by-side relationship upon placing the frame in substantially horizontal position.

2. For a well-type freezing compartment, an ice cube forming unit adapted for introduction into and removal from said compartment, said unit comprising a substantially rectangular frame having side portions and end bars, one of said end bars having means engageable with portions of said compartment to suspend the frame substantially vertically therein, a plurality of elongated tray-like members of a size to fit between said side portions of the frame, and interengageable elements respectively carried by adjacent portions of the ends of said tray members and the side portions of said frame providing a pivotal connection therebetween so that said tray members automatically assume an upright superimposed relationship upon placing the frame in substantially vertical position and automatically assume an upright side-by-side relationship upon placing the frame in substantially horizontal position.

3. For a well-type freezing compartment of a domestic refrigerator cabinet, an ice cube forming unit adapted for introduction into and removal from said compartment, said unit comprising a substantially rectangular frame having side portions and end bars, one of said end bars extending beyond the side portions of the frame to provide means engageable with portions of the compartment to suspend the frame substantially vertically therein, sets of oppositely disposed pins projecting inwardly of the frame side portions substantially at right angles thereto, a plurality of elongated tray-like members, one for each of said sets of pins, partitions disposed transversely in each of said tray members and positioned at spaced points along the length thereof to define

ice cube forming sections therein, and hangers carried by the ends of each of said tray members and engageable with one of said sets of pins to provide a detachable pivotal connection therebetween so that said tray members automatically assume an upright superimposed relationship upon placing the frame in substantially vertical position and automatically assume an upright side-by-side relationship upon placing the frame in substantially horizontal position.

4. An ice cube forming unit comprising a substantially rectangular frame having side portions and end bars, sets of oppositely disposed pins projecting inwardly of the frame side portions substantially at right angles thereto, an elongated tray-like member for each of said sets of pins, partitions disposed transversely in each of said members and positioned at spaced points along the length thereof to define ice cube forming sections therein, and hangers carried by the ends of each tray member engageable with one of said sets of pins to provide a detachable pivotal connection therebetween constructed and arranged so that upon placing the frame in substantially vertical position said tray members automatically assume an upright superimposed relationship and upon placing the frame in substantially horizontal position said tray members automatically assume an upright side-by-side relationship.

5. A refrigerator comprising a cabinet including a bottom compartment portion having back, side and front walls and a smaller upper compartment portion open at the top having back and side walls, and a front wall set back from the front wall of said bottom compartment, a closure member for the top opening of said upper compartment portion, a substantially horizontal fixed top wall overlying said bottom compartment portion forwardly of the upper compartment front wall and providing a work-table surface, a cooling coil in said upper compartment portion extending adjacent and along the walls of at least a part thereof, and an ice cube forming unit supported within said cooling coil and removable therefrom through the top opening of said upper compartment portion of the cabinet when the closure member therefor is open.

6. A refrigerator comprising a cabinet including a bottom compartment portion having back, side and front walls and a smaller upper compartment portion open at the top having back and side walls, and a front wall set back from the front wall of said bottom compartment, a closure member for the top opening of said upper compartment portion, a substantially horizontal fixed top wall overlying said bottom compartment portion forwardly of the upper compartment front wall and providing a work-table surface, a cooling coil in said upper compartment portion extending adjacent and along the walls of at least a part thereof, and an ice cube forming unit comprising a frame and ice trays carried thereby suspended within said cooling coil by engagement of a portion of said frame with a surface of the cabinet upper compartment portion, said unit being insertable in and removable from said upper compartment respectively by lowering and raising said unit vertically through the top opening of the said upper compartment when the closure member therefor is open.
